UNITED STATES PATENT OFFICE.

SAMUEL C. HOEY, OF WILKINSBURG, PENNSYLVANIA, ASSIGNOR TO WESTINGHOUSE ELECTRIC & MANUFACTURING COMPANY, A CORPORATION OF PENNSYLVANIA.

TELEGRAPH KEY.

Application filed December 14, 1918. Serial No. 266,707.

To all whom it may concern:

Be it known that I, SAMUEL C. HOEY, a citizen of the United States, and a resident of Wilkinsburg, in the county of Allegheny and State of Pennsylvania, have invented a new and useful Improvement in Telegraph Keys, of which the following is a specification.

My invention relates to telegraph keys, having particular relation to keys for use on portable wireless-transmission sending sets, and it has for its object to provide a simple, rugged and inexpensive device of the character indicated that shall be especially adapted for outdoor use in inclement weather.

In the accompanying drawings, Fig. 1 is a plan view of a key constructed in accordance with my invention and mounted within a casing enclosing a sending set; Fig. 2 is a plan view and Fig. 3 is a side view, partially in section and partially in elevation, of the key shown in Fig. 1; and Fig. 4 is a detail view showing the bottom of the key box in elevation and the contact members mounted on the supporting base and co-operating therewith.

Heretofore, it has been customary in manufacturing telegraph keys adapted for field service, to provide the key lever with a hinge joint so that it may be moved to project from the enclosing casing when desired. However, such a key must always be projecting out over the edge of the enclosing casing or must have one portion of the lever bent to a position substantially at right angles to the other portion, thus occupying a larger amount of much needed space on the box on which it is mounted than is desirable. Also, if a lever arm of this character is of heavy construction, it is clumsy and unnecessarily heavy, and if lightly constructed, the hinge therein tends to become loose and the key loses the positive response to the touch so necessary for this type of work.

By my invention, I provide a lightly constructed key in which the actuating lever is a solid arm and which can be used with the lever projecting from the casing or with the lever entirely enclosed therein without occupying an undesirably large amount of space.

For a further understanding of my invention, reference may be had to the drawings, in which I show a key consisting of an ac-

tuating lever 1 and a box 2 comprising a shaft 3 upon which is mounted the actuating lever 1 and an arm 4 supporting a movable contact member 5. The amplitude of movement of the lever 1 is adjusted by means of a set screw 6. A contact member 7 is mounted upon a base member 8 of insulating material and is engaged by the contact member 5 upon actuation of the lever 1. The base member 8 has a cylindrical projection 9 mounted in a circular opening 10 in a base member 11, which is the instrument base in the box. The key lever and key box may both be rotated about the axis of this opening when desired, an opening 12 in the side of the enclosing casing permitting the key to project therefrom with the box closed. The key lever 1, in its rotated position, is shown in dot-and-dash lines in Fig. 1. A metallic plate 13 is fastened to the base portion 9 to prevent the key box from becoming displaced from the opening 10 and is electrically connected to the contact member 5 to serve as a collector plate when engaged by a metallic brush 14 that is mounted upon the stationary base 11. A contact member 15, that is connected to the contact member 7 and is insulated from the plate 13, engages an arcuate shaped contact member 16 which is also mounted upon the stationary supporting member 11.

By inverting the key box casting before attaching the lever arm 1 thereto, the lever may be mounted upon the opposite side of the key box, the only alteration necessary being to provide a new hole for the set screw 6.

While I have shown only one form of my invention, it will be obvious to those skilled in the art that it is not so limited but is susceptible to various minor changes and modifications without departing from the spirit thereof and I desire, therefore, that only such limitations shall be placed thereupon as are imposed by the prior art or are specifically set forth in the appended claims.

I claim as my invention:

1. A telegraph key comprising an actuating lever and a rotatable base member, and two collector members mounted on said base and two stationary contact members adapted to engage said collector members, co-operating collector members and contact members being continuously in engagement for all positions of said base member.

2. A telegraph key comprising an actuating lever mounted on a key box, and a support therefor, said key box being rotatably mounted on said support and means for maintaining the same connections for all positions of said key box.
3. A telegraph key comprising an actuating lever mounted on a key box, an insulating support therefor, said key box being rotatably mounted on said support, a collector ring mounted on said key box, and a brush adapted to engage said collector ring and mounted on said support.
4. A telegraph key comprising an actuating lever mounted upon a key box, an insulating support therefor, said key box being rotatably mounted on said support, a collector ring and a brush mounted upon said key box to engage a correspondingly disposed brush and collector ring respectively mounted on said support.
5. In an intelligence-transmission sending device, a key mounted on a rotatable key box, and an enclosing casing provided with an opening, said key box being so positioned within said casing as to cause said key to be enclosed within said casing when at one end of its arcuate path and to project therefrom when at the other end of its path.
6. The combination with a telegraph key, of a movable supporting member therefor, and an instrument case in which said supporting member is mounted, the movement of said supporting member being such that the handle of said key may be either en-
- closed within said case or projected outside thereof.
7. The combination with a supporting base, of a member movably secured to said support, a telegraph key carried by said movable member, and means for maintaining the same electrical connections for all positions of said movable member.
8. In a telegraph key, a movable key box, a key carried by said box and accessible from the outside thereof, said key having its circuit-interrupting contacts positioned within said box, and means for maintaining the same electrical connections for all positions of said box.
9. The combination with a movable box, of a key comprising an operating element, a collector ring, and a brush mounted upon said key box to engage a correspondingly disposed brush and collector ring respectively mounted on said support.
10. The combination with a supporting base, of a key box movably secured thereto, a telegraph key carried by said movable member, said key having its circuit-interrupting contacts positioned within said box, and means for insuring the same electrical connections for all positions of the box.
11. In testimony whereof, I have hereunto subscribed my name this 2nd day of December, 1918.

SAMUEL C. HOEY.
